UNITED STATES PATENT OFFICE.

HUGO O. STAMP, OF MILWAUKEE, WISCONSIN, ASSIGNOR TO THE STAMP MACHINE COMPANY, OF MILWAUKEE, WISCONSIN.

SELF-LOADING CONCRETE MIXING AND DISTRIBUTING MECHANISM.

Application filed September 8, 1919. Serial No. 322,393.

To all whom it may concern:

Be it known that I, Hugo O. Stamp, a citizen of the United States, and resident of Milwaukee, in the county of Milwaukee and 5 State of Wisconsin, have invented certain new and useful Improvements in Self-Loading Concrete Mixing and Distributing Mechanism; and I do hereby declare that the following is a full, clear, and exact description 10 thereof.

My invention relates to new and useful improvements in machines for use in connection with concreting operations, and it is more particularly directed to the provision 15 of a self-loading concrete mixing and distributing machine of the general type embodied in application for patent filed by me May 6, 1918, Serial No. 232,785, now Patent 1,349,231, Aug. 10, 1920, and adapted for 20 laying concrete roadways.

It is in general the object of my invention to improve the construction and to increase the economic efficiency of machines of this character particularly with respect to 25 adapting the machines for continued operation with a minimum expenditure of manual labor, under the widely varying conditions encountered in laying concrete roads.

Numerous difficulties are encountered in 30 mechanically conveying the concrete aggregate to the mixer from piles arranged along the roadway in advance of the mixer, such difficulties arising from the economic necessity of a practically continuous operation 35 of the mixer and from the large volume and definite proportions of the aggregate constituents which must be fed to the mixer.

The mechanisms for mechanically conveying and mixing the aggregate material must be 40 readily transportable in nature to adapt them for movement in the road-laying job and for travel from one job to another, and they must be reliable in operation since they constitute one link of a chain of operations 45 which must be kept continuously in action under the economic conditions imposed, and which extends in its ramifications even to railway transportation conditions. The piles of aggregate along the roadway are 50 deposited by trucks or wagons from the base of supply. The chief difficulty in mechanically conveying the material resides in the variation of relative volume of the aggregate material laid along the various sections of the roadway, and to meet this diffi-

culty in the present machine and in my previous machines, I provide an elongated conveyer traveling in advance of the mixer and of maximum length consistent with practicability of transportation, the length of this 60 conveyer mechanism being thus approximately forty feet. Road-laying operations have heretofore been carried out by shifting the mixer in successive steps over the sections of roadway for distances of approximately twenty feet, a series of mixes being effected between each shifting operation sufficient to provide a mixed concrete for the section of roadway over which the mixer 70 and loading conveyer mechanism has previously advanced, the mixer and loading mechanism being advanced over the succeeding section of roadway at the termination of each series of mixes. The disadvantages 75 which are present in this operation are, first,

the loss of operative time incidental to the steps of shifting the mixer, and second, in the use of my loading mechanism, the loss 80 in variation capacity of the loading conveyer mechanism, since, at and adjacent the termination of a series of mixing steps for a section of roadway, the aggregate along the roadway must necessarily be used up a distance approximately equal to the length 85 of the laid section of roadway, and hence a limited stretch of the conveyer mechanism equal to the difference between its length and the section of roadway, or about one-half of the length of the conveyer mechanism, alone can be used to compensate for 90 the variation of the volumes in which the piles of aggregate material are laid out.

It is therefore primarily the object of my invention to provide a method and apparatus for collecting, mixing and distributing the concrete material which avoids these recited disadvantages, and it is more particularly my object to overcome these disadvantages by providing an arrangement 95 for slowly moving or inching the entire apparatus along the roadway at a rate of movement approximately equal to the rate of progression of the concrete laying operation, this movement being automatically effected and thus avoiding the necessity of stops for shifting the conveyer and utilizing at all times the entire length of the conveyer mechanism to compensate for variations of the volume of the laid-out piles of 100 aggregate. Since the rate of progression of 105 aggregate. Since the rate of progression of 110

the concrete laying operation varies from fifty to one hundred feet per hour under different conditions, it is seen that my novel operation of advancing the mixer is entirely 5 distinct from any other heretofore contemplated arrangement for propelling the mixer, or mixer and conveyer, wherein if the mixer is propelled even at an exceedingly slow speed of one-half mile per hour, 10 such speed would be from twenty-five to fifty times faster than my rate of continuous movement of the mixer, and it would be impossible in any existing mechanism to throttle or slow down the speed of movement 15 to my requirements.

It is further my object to provide a simple and effective mechanism for procuring this slow inching movement within certain variable limits to provide for different 20 sired rates of progression of the laying operation, and it is more particularly my object to provide, in this connection, means operative independently of said inching means for procuring a normal rate of travel 25 of the apparatus to make up for lost space incidental to advance of the rate of progression of the laying operation with respect to the rate of inching propulsion of the apparatus, and to adapt the apparatus 30 for transportation generally.

Another and important object of my invention resides in the provision of an arrangement whereby the measuring, mixing and discharge of the batches of concrete 35 may be carried out in an entirely automatic manner in regular cycles.

A more detailed object in this connection resides in the provision of means for varying the relative lengths of time elapsing between the steps of the cycle to thus provide 40 for differing mixing conditions, as it is desirable at times to vary both the amount of aggregate in the mix, and the length of time which the aggregate is mixed.

45 A further important object resides in the provision of a lateral conveyer mechanism operable in conjunction with a main longitudinal conveyer of the load conveyer means, which may be automatically moved 50 along the main conveyer structure at a variable speed.

Another object in connection with the lateral conveyer resides in the provision of an arrangement whereby said lateral conveyer 55 mechanism is wholly supported by the main longitudinal conveyer structure and whereby said lateral conveyer mechanism receives the power from the traveling portions of the main conveyer structure.

60 With the above and other objects and advantages in view, my invention resides more particularly in the novel combination, formation and arrangement of parts herein-after described and particularly pointed out 65 in the appended claims.

In the accompanying drawings:

Figure 1 is a side elevational view of the truck portion of a concreting machine embodying my invention, portions being removed as indicated in general by the line 70 1-1 of Figure 2.

Figure 2 is an enlarged transverse sectional view on planes indicated by the broken line 2-2 of Figure 1.

Figure 3 is a detail sectional view through 75 the automatic operating mechanism on the line 3-3 of Figure 2.

Figure 5 is a plan view of the lateral conveyer and a portion of the main longitudinal conveyer of the feeding conveyer mechanism.

Figure 6 is a detail sectional view on the 85 line 6-6 of Figure 5, showing the adjustable support for the lateral conveyer.

Figure 7 is a partly diagrammatic elevational view of the lateral conveyer on a plane indicated by the line 7-7 of Figure 5.

Figure 8 is a longitudinal sectional view on the line 8-8 of Figure 5.

Figure 9 is a transverse sectional view on the line 9-9 of Figure 5.

Figure 10 is an elevational view of the 95 longitudinal conveyer.

Referring now more particularly to the accompanying drawings, certain salient features of the machine which constitute one embodiment of my present invention are 100 shown in detail in my said co-pending application and hence the specific showing of such features is avoided in the present instance. The main frame of my machine comprises 105 side sills 20 and cross sills 21 and is supported at its forward end by wheels 22, the rear end of the truck being supported by traction wheels 23 mounted on a shaft 24 which is journaled in bearings depending 110 from the side sills 20 and which carries 115 sprocket wheels 25 driven from similar sprocket wheels 26 mounted on a shaft 27 journaled in the rear of the axle shaft. A framework 28 is carried by the truck sills and a cylindrical separator screen 29 is carried 120 by the upper intermediate portion of the said framework, one end of the screen carrying a shaft 30 journaled in a bracket 31 on the framework and driven from a transverse shaft 32 also journaled in said 125 bracket. The other upward end of the screen rides on rollers 33 carried by the framework. Disposed under this screen is a storage hopper 34 which receives sand discharged through the screen and at the rear 130 end of this hopper is disposed a second storage hopper 35 which receives the material which passes through the screen and is discharged from the end thereof. A cement storage hopper 36 is preferably dis-

posed at the forward end of the sand storage hopper and may be supplied with cement in any suitable manner (not shown). Cement, sand and stone measuring hoppers 37, 38 and 39 respectively are disposed under the storage hoppers, and in the present instance these measuring hoppers are disposed directly under the mouths of the storage hoppers and in such proximity as to prevent escape of material from the open storage hoppers when the measuring hoppers are filled. A common belt conveyer 40 is disposed directly under the measuring hoppers, being trained about a drive roller shaft 41 at its forward end and about an idle roller shaft 42 at its rear end and this belt conveyer is adapted to discharge into a mixing drum 43 which is rotatably mounted on rollers 44 supported by the main truck sills. As in my aforementioned application for patent, a feeding conveyer yoke 45 is mounted at the forward end of the machine, said yoke having a sleeve 46 at its upper end journaled on a drive shaft 47 which is mounted in a bracket 48 extending forwardly from the framework, while the lower end of the yoke is pivoted at 49 on the truck frame. This yoke carries a boot 50 for receiving discharge of work material from the feeding conveyer and discharging said material into a chute 50' which feeds an elevator conventionally shown at 51 and carried by an upper transverse drive shaft 52 and a lower idle sprocket shaft 53, all of this structure being shown in detail in my said co-pending application.

Taking up now the means for driving the various mechanisms set forth, an engine 54 is mounted on the truck wheels, preferably under the hopper structure and adjacent the mixing drum and this engine has sprocket connection 55 with a longitudinal shaft 56 journaled at the side of the framework. The rear end of this shaft carries a pinion 57 meshing with a gear ring 58 on the periphery of the mixing drum to thus provide for continuous rotation of the drum. The forward end of the shaft 56 has bevel gear connection 59 with a counter-shaft 60 journaled transversely at the forward end portion of the frame. The wheel drive shaft 27 is driven from this counter-shaft by inching mechanism later to be described.

The counter-shaft carries at one end a sprocket wheel 61 which is controlled by a conventionally shown clutch 62 and which has trained thereabout a sprocket chain 63 extending to a sprocket wheel 64 on a counter-shaft 65 which is journaled above the yoke carrying shaft 47 and has bevel gear connection 66 therewith. The shaft 47 also carries a gear wheel 67 for driving the yoke carried feeding conveyer mechanism as shown more clearly in my aforementioned patent. The counter-shaft 65 also

has sprocket chain connection 68 with the elevator drive shaft 52 and said elevator drive shaft 52 in turn has sprocket chain connection 69 with the drive counter shaft 32 of the screen. Thus, the clutch 62 controls simultaneous continuous operation of the feeding conveyer mechanism, elevator and screen. A pinion 70, controlled by a clutch 71 is also mounted on the counter-shaft 60 for driving a hoist drum gear 72 shown more particularly in Figure 1, said hoist drum controlling the lifting of the feeding conveyer.

A distributing conveyer mechanism is carried by the rear portion of the main truck and comprises in the present instance a boom 73 carried by and swing horizontally from a drive shaft 74 for a sprocket chain 75 longitudinally carried by the boom and adapted to shift a batch receiving conveyer bucket 76 which is suspended from the boom, the shaft 74 being driven by clutch gear connection 77 with a shaft 78 which is in gear connection with the gear ring 58 of the mixer drum. This distributing conveyer mechanism is shown more particularly in my said co-pending application for patent, the boom 73 being supported at its outer end (not shown) by a cable 79 extending from the upper rear portion of the truck frame.

Having set forth the general relation of the parts of my machine, I will now proceed to describe the various particular phases of my present invention.

The loading conveyer means.

As in my said co-pending application, the loading conveyer means of my machine includes a main longitudinal conveyer frame having upper and lower trackways for the stretches of the main conveyer buckets, the lower trackway comprising angle plates 80 having their upper edges turned inwardly and downwardly to provide deflecting portions 81. These track plates are connected by upright side bars 82 with upper track plates 83 which are Z-shape in cross section, the bars 82 and lower track plates 80 being further connected by transverse brace sills 84. The track frame is connected with the yoke 45 by upwardly inclined track bars 85 having their upper ends pivoted at 86 to the arms of the yoke 45 and having their lower ends secured to the lower track plates 80. To provide a wheeled support for the outer end portion of the conveyer frame, pairs of superposed levers 87 are pivoted to and extend outwardly in parallelism from the outer portion of the conveyer frame, said levers being pivotally connected with transverse bars 88 in which are journaled the standards 89 of a pair of ground wheels 90, said standards being connected together as in my said co-pending application, by link mech-

anism 91 to produce a simultaneous turning movement. It is thus seen that in vertical relative movement with respect to the wheels and conveyer frame, to either raise or lower 5 the conveyer frame with respect to the ground, the standards 89 of the wheels are maintained in vertical position whereby a proper travel of the wheels is assured in whichever direction they are turned. This 10 relative movement of the wheels and conveyer frame is effected in the present instance by an angle lever 92 which is pivoted to the rear end of the frame and which carries a roller 93 on one arm engaging a lower lever 87. The other arm of the lever 92 extends upwardly and has secured thereto a cable 93 which extends rearwardly of the conveyer frame and is trained about a roller 94 at the rear portion of the conveyer frame 15 and secured to a main hoist cable 95. This main hoist cable is secured to the upper portion of the main truck frame and is extended downwardly therefrom and through a pulley 96 to which is secured a cable 97 extending 20 to the inner portion of the conveyer frame. The main cable 95 is extended rearwardly from this pulley 96 and trained about a pulley 98 and thence extended to a hoist drum 99 operated by the gear 72. Thus, 25 upon drawing on the cable 95, both end portions of the main conveyer frame will be simultaneously lifted.

The conveyer buckets 100 of the main longitudinal conveyer are carried by endless side sprocket chains 101, each bucket being secured to said sprocket chains at two adjacent corners, and sprocket rollers 102 are carried by the chains at the junctures of the links. The chains are trained about conventionally shown idle sprocket wheels 103 at the outer end portion of the frame and are trained about drive sprocket wheels 104 carried by a transverse shaft 105 of the yoke 45, said shaft being driven from the aforementioned gear wheel 67 in the manner of my 30 said previous application for patent. The buckets travel rearwardly on the lower trackway with their mouths disposed upwardly and with their ends which are free 35 from the sprocket chain disposed rearwardly. The buckets are supported in this travel by wheels 106 at their free ends which ride on the track plates 80, the secured ends of the buckets having ledges 107 which seat 40 on the ends of the preceding buckets. As the buckets move about the drive sprockets 104 they discharge into the boot 50 and said buckets are returned in inverted position on the upper trackway of the conveyer frame, 45 said buckets riding in this return movement on the sprocket rollers 102 of the chain, said sprocket rollers engaging the inturned lower portions of the Z-shaped track plates 83.

In the present embodiment of my invention, I employ in connection with this main

conveyer structure, a lateral conveyer mechanism which is carried wholly by the track frame of the main conveyer structure, and which, to this end, includes a carriage comprising the side sills 108 and front end sill 109, the ends of the side sills terminating in bearings for axles 110 on which are mounted flanged wheels 111 riding on the out-turned upper portions of the Z-shaped upper track plates 83. A power shaft 112 is transversely journaled in the rear portion of the carriage and the shaft carries sprocket wheels 113 which mesh with the upper return stretches of the bucket conveyer chains 101. An arm 114 extends outwardly at substantially right angles from one side of the conveyer and is connected at its outer end with a second arm 115 which extends obliquely from the end portion of the carriage adjacent the shaft 112. A conveyer drive shaft 116 is journaled in the inner portion of the oblique arm 115 and is driven from the shaft 112 by bevel gears 117. A conveyer support bar 118 has its inner end pivotally mounted on the shaft 116, and also carried on the shaft in fixed relation thereto is a sprocket wheel 119 around which is trained a chain 120 which is also trained about a sprocket wheel 121 on the outer end of the support bar, and which carries a series of buckets 122. The lateral conveyer extends obliquely downwardly and laterally from its connection with the main conveyer structure and the lateral conveyer is afforded and adjustable support for its outer portion by a yoke 123 which has its depending arms in pivotal connection with arms 124 extending laterally from the intermediate portion of the conveyer support bar 118, said yoke being suspended from a screw 125 which is passed through the juncture of the carriage arms 114 and 115 and which carries a nut 126 which may be rotated to vary the suspension of the lateral conveyer. This lateral 50 conveyer discharges into a chuteway 127 which is carried by the conveyer carriage at the side of the main conveyer frame to thus direct the material conveyed between the trackways and into the buckets on the lower trackway, an inclined guide plate 128 being preferably secured to the adjacent side of the main conveyer frame and co-operating with the deflecting portion 81 of the adjacent track plate 80 to direct the material 55 into the buckets.

For gradually advancing the carriage along the main conveyer frame at a variable speed, a transverse shaft 129 is journaled transversely in the forward portion of the carriage and has fixed thereon at one end a gear wheel 130 which meshes with rack teeth 131 cut into the upper out-turned portion of the adjacent Z-shaped track plate 83. A ratchet wheel 132 is fixed on the intermediate portion of the shaft 129, and a crank 60

arm 133 is journaled on the shaft adjacent the ratchet wheel and is connected by a pitman 134 with a cam ring 135 mounted on a loose cam sleeve 136 on the shaft 112. This cam sleeve is engagable by a clutch member 137 splined on the shaft and controlled by a spanner lever 138. Thus, when the cam sleeve is clutched to the shaft, the crank arm is reciprocated and this reciprocating movement is translated into rotation of the shaft 129 to advance the carriage by a pawl 139 pivoted on the crank arm and engaging the teeth of the ratchet wheel 132. Variation of the speed of propulsion effected by this drive arrangement is procured by a lifting dog 140 which is carried on a rock arm 141 pivoted on the shaft 129, said dog being insertible between the pawl 139 and the ratchet wheel to lift the pawl in its idle stroke and thus control the engagement of the pawl with the teeth of the ratchet wheel. The position of the dog 140 is controlled by a turn buckle link 142 pivotally connected with rock arm 141 and with the front sill 109 of the carriage. The shaft 129 carries a crank handle 143 whereby it may be rotated manually to move the lateral conveyer rearwardly, it being understood that the pawl 139 could be disengaged from the ratchet wheel, and under certain conditions the carriage may be simply pushed rearwardly. To provide for a rapid forward movement of the lateral conveyer mechanism, as in moving between two spaced piles of aggregate, a brake drum 144 is mounted on one end of the shaft 112 and carries a brake band 145 which is secured to a lever 146 pivoted to the carriage. Thus, by applying braking pressure to the shaft 112, the sprocket wheels 113 will be locked against rotation and the lateral conveyer carriage will be advanced at the speed of movement of the main conveyer chains 101 by the interlocking engagement of the sprocket wheels 113 therewith. It will, however, be particularly noted that irrespective of the various positive forward feeds which I have described, the direction of movement of the sprocket chains 101 and their drive connections with the lateral conveyer mechanism exert a positive tendency to advance the lateral conveyer mechanism, and may under certain conditions serve to provide the means for urging the lateral conveyer into piles of aggregate as it is being dug.

The propelling mechanism.

The propelling mechanism of my machine is adapted to advance the machine at an exceedingly slow rate of movement corresponding to the rate of progression of a road-laying operation, and also to advance the machine at a normal speed of travel, the mechanism for effecting the slow or inching advancing movement being operable

continuously in operation of the machine and independently of the rapid propelling means. To this end, a counter shaft 147 is journaled transversely in the main truck structure of the machine between the power shaft 60 and the axle drive shaft 27 and this shaft is driven by a sprocket connection 148 from the shaft 60, said sprocket connection being controlled by a clutch member 149 splined on said shaft 60. A pair of gears 150 and 151 are mounted on the axle drive shaft 27, the gear 150 meshing with an idle pinion 152, and the pinion and the gear 151 are selectively engageable by a pinion 153 splined on a shaft 147 to procure forward or rearward propulsion of the truck.

The slow inching advance of the truck is procured in the present instance by means of a ratchet wheel 154 fixed on the shaft 147 and engageable by a pawl 155 carried on one arm of an angle lever 156, the other arm of said angle lever being connected by a pitman 157 with a ring mounted on a cam collar 158 which is loose on the shaft 60 and which is engageable by a clutch member 159 splined on the shaft 60. This driving mechanism is similar to the driving means of the lateral conveyer carriage, being rendered adjustable in nature by a dog 160 carried on an arm 161 pivoted on the shaft 147, said dog being movable between the ratchet wheel and the path of the pawl 155, and being controlled in its position by a turn buckle link 162 pivoted to the arm 161 and to a portion of the truck frame. It will however, be appreciated that other slow drive means may be employed, such as a worm drive, the particular value of the present drive means being its readiness of adjustment to meet the different rates of progression of concrete laying operations.

The automatic mixing mechanism.

To control flow of aggregate material from each of the storage hoppers into the corresponding measuring hopper, each storage hopper is provided with an apertured bottom over which is slidable a valve plate 163 having gear and ratchet connection 164 with a control shaft 165 journaled at one side of the storage hopper structure. Thus upon sliding the valve plate to open position, the proper proportions of aggregate and cement will flow by gravity into the measuring hoppers. Flow of aggregate from the measuring hoppers onto the continuously operative conveyer 40 extending to the mixer, is controlled by a valve plate 166 slidable over the apertured bottom of each measuring hopper and connected by a crank 167 with a shaft 168 journaled at the side of the measuring hopper structure. Discharge of material from the mixer drum

43 is controlled in the usual manner by a chute 169 pivoted at the discharge mouth of the mixing drum on a shaft 170, said chute when tilted to discharging position 5 being adapted to discharge into the bucket 76 of the distributing conveyor. A water reservoir tank 171 is carried at the upper rear portion of the truck frame and is connected with a three-way valve 172 from 10 which extends a supply pipe 173. A pipe 174 also extends from the valve and is directed into the inlet mouth of the mixing drum.

To operate all of these control means successively in cycles to thus effect a series of automatic mixing operations, an endless chain 175, carrying an actuator 176, has its paths of movement so arranged with respect to various trip levers connected with 15 the control means as to effect a complete mixing cycle. This chain is mounted on an outstanding vertically elongated bracket 177 carried by the truck frame. A shaft 178 is journaled at the top of the bracket 20 and carries a sprocket wheel 179 around which is trained a chain 180 driven from a sprocket wheel 181 on the main longitudinal power shaft 56. The shaft 178 also carries a sprocket wheel 182 around 25 which is trained the upper portion of the actuator chain 175. A pair of idle sprocket wheels 183 are disposed at the outer side stretch of the actuator chain, and said chain is trained about these sprocket wheels and 30 extended therebetween to form an adjustment loop 175^a intermediately of its outer side stretch which is trained about a sprocket wheel 184 adjustably carried by an outwardly extending slotted bracket 185. The 35 lower portion of the actuator chain is trained about an idle sprocket wheel 186 also adjustably carried by a depending slotted bracket arm 187. A pair of idle sprocket wheels 188 are disposed at the inner side 40 stretch of the chain and the chain is trained about these sprocket wheels and extended therebetween to form a second adjusting loop 189 also trained about an adjustably mounted idle sprocket 190. The length of 45 the chain may thus be varied at different points to vary the length of time which is consumed by the actuator 176 carried by the chain in traveling from point to point.

The first step in the automatic cycle is to 50 close the valve plate 163 of the main hopper structure, and this is accomplished by a lever 191 pivoted at the outer side of the chain bracket 177 and having one arm extended toward the actuator chain and having a fork 192 engageable by the actuator to 55 rock the lever. An upstanding arm of the lever is connected by a link 193 with a crank arm 194 on the valve control shaft 165.

60 The next step, of opening the valve plate

of the measuring hopper, is effected by a lever 195 pivoted also at the outer portion of the bracket 177 and carrying a fork 196 engageable by the actuator, the forks of both of these levers being engaged by the 70 actuator at the lower portion of the outer stretch of the chain. The lever 195 is connected by a link 197 with a crank arm 198 depending from the control shaft 168.

The next two steps are to successively 75 close the valves of the measuring and storage hoppers after sufficient time has elapsed to permit complete discharge of the measuring hoppers onto the conveyor 40, this is 80 accomplished by fork extensions 199 and 200 on the levers 195 and 191 respectively which are engageable by the actuator in traveling upwardly at the lower portion of the inner stretch of the chain 175. The adjustment afforded by the sprocket wheel 186 serves to 85 vary the time allowed for emptying the measuring hoppers, variation of this time being necessary on account of differing measuring loads of the hoppers, and other conditions. To effect the initial step of 90 rocking the chute 169 to discharge the mixing drum, a lever 201 is pivoted at the outer upper portion of the bracket 177 and is engageable by the actuator 176 in traveling down the upper outer stretch of its chain to 95 rock said lever, this rocking motion being transmitted through a link 202 to a crank 203 on one end of a longitudinal shaft 203^a having a crank 203^b on its other end from 100 which a second link 204 extends to a crank arm 205 on the pivot shaft 170 of the chute. The lever 201 is rocked in a reverse direction to swing the chute back to closing position by a link 206 pivoted to its outer portion and connected with an arm 207 pivoted 105 adjacent the lever 195 which controls the valve means of the measuring hoppers. The arm 207 carries a laterally extending pin 208 whereby, as the valve means of the measuring hoppers is opened, the arm 207 110 will be rocked to close the chute. The water supply valve 172 is controlled by a lever 209 intermediately pivoted adjacent the lever 195, this lever being connected at its outer end by a link 210 with a crank 211 on one end of a longitudinal shaft 211^a having a crank 211^b on its other end which is 115 connected by a second link 212 with a crank arm 213 on the stem of the valve 172. The lever 209 is rocked to open the valve upon 120 rocking movement of the lever 191 in closing the valve of the storage hoppers, by a slotted link 214 extending from the lever 191 and receiving in its slotted portion a pin 215 on the outer portion of the lever 209. Said lever 209 is rocked to close the valve by a pin 216 on its inner portion extending 125 into the path of valve opening movement of the lever 195. The adjustment afforded by the shiftable sprocket wheel 190 provides 130

for a variable length of time which the mixing operation is permitted, in accordance with different mixing requirements. The adjustments afforded by the shiftable 5 sprocket wheel 184 and the adjustment loop 175 of the actuator chain provides for a variable length of time which the mixer is permitted to discharge.

Summarizing now the general operation 10 of the present embodiment of my improved machine, the machine is continuously moved along the road by the inching or slow advancing mechanism described at a rate of speed approximately equal to the rate of 15 progression of the concrete laying action, thus maintaining the distributing conveyer mechanism at all times in proper relation for the progressive distribution of concrete on the roadway, and inasmuch as the rate 20 of progression varies in accordance with the width of the roadway and other conditions, the inching mechanism of the machine is adjusted accordingly. Should, however, the rate of progression of the laying operation 25 advance upon or lag behind the rate of inching movement of the machine, said machine may be halted or speeded up in travel at intervals to compensate for this difference. The necessity of halting the operation at 30 short intervals to shift the machine is avoided, and it is particularly noted that in my improved method of laying the roadway the actual point of deposit of the mixed 35 concrete on the roadway may be maintained a sufficient distance rearwardly of the machine so as to provide access at all times to the sub-grade or concrete receiving surface, to smooth over any portions thereof which may have become disturbed incidental to 40 travel of trucks thereover in depositing material, or from other cause. The continuous advancing movement of the machine also utilizes at all times the full length of the main loading conveyer to compensate for 45 variation in the manner in which the piles of aggregate are laid out along the roadway, thus insuring an adequate supply of aggregate to the storage hoppers 34 and 35 of the machine, and inasmuch as the aggregate is 50 usually laid out approximately in uniformity, the continuous advancement of the machine maintains the gathering and conveying mechanism, constituted by the main and lateral conveyers, in operative relation 55 to the work material. The feeding movement of the lateral conveyer on the main conveyer is utilized to compensate for variations in the amount of laid out piles of aggregate with respect to the rate of 60 progression, the operation of said lateral conveyer may be supplemented by manual shoveling directly into the lower stretch of the main conveying buckets, and adjustment of the speed of feeding movement of the 65 lateral conveyer compensates for different

degrees of variation of the supply of aggregate material, thus adapting the machine for effective and economical operation under exceedingly wide variations of operative conditions.

Several batches of aggregate material normally are maintained in the storage hoppers 34 and 35 at all times, and as the machine progresses, properly proportioned batches of material are measured from this storage supply and discharged into the mixing drum, which is subsequently automatically discharged into the bucket 76 to thus procure progressive automatic cycles of the mixing operation. In each of the cycles, the 70 flow control means of the storage hoppers is open to discharge into the measuring hoppers 38 and 39 and simultaneously the previously mixed batch in the mixer 43 is discharged by rocking the discharge chute 169 of the mixer. The flow control means of the storage hoppers is then closed, the flow control means of the measuring hoppers is 75 opened and simultaneously the discharge chute 169 of the mixer is rocked to position preventing discharge from the mixer, water being also automatically introduced into the mixer at this time, all by means of the mechanism heretofore described.

I have thus effected a great economy in 80 the amount of attention and manual labor heretofore found necessary in concreting operations.

While I have shown and described a preferred embodiment of my invention, it will 85 be appreciated that various changes and modifications of structure and operation may be employed to meet differing conditions of use, without departing in any manner from the spirit of my invention.

What is claimed is:

1. In a machine of the class described, a main longitudinal conveyer including an elongated frame, a truck carried by and movable along said frame, and a lateral conveyer wholly supported by said truck and extending obliquely downward and forward from its point of discharge on the main conveyer.

2. In a machine of the class described, a main longitudinal conveyer including an elongated frame, a truck carried by and movable along said frame, a lateral conveyer wholly supported by said truck and extending obliquely downward and forward from its point of discharge on the main conveyer, and means for adjusting the vertical angularity of the lateral conveyer.

3. In a machine of the class described, a longitudinal conveyer mechanism including traveling stretches, a lateral conveyer movable along the longitudinal conveyer, means operable by the longitudinal conveyer mechanism for moving the lateral conveyer along the longitudinal conveyer at a speed of move-

- ment less than the speed of movement of the traveling stretches of the longitudinal conveyer, and means for securing the lateral conveyer to one of the traveling stretches of the longitudinal conveyer for travel therewith at the speed of said traveling stretches.
4. In a machine of the class described, the combination of a truck portion, a longitudinal conveyer frame, a lateral conveyer movable along said longitudinal conveyer frame, a drive cable for said lateral conveyer, the driving strand of said cable moving forwardly whereby to urge the lateral conveyer into engagement with the material piles, and power driven means for feeding said lateral conveyer forward.
5. A machine of the class described including a main longitudinal conveyer, a lateral conveyer movable along the longitudinal conveyer and arranged to discharge on the longitudinal conveyer, means operable by the longitudinal conveyer for driving the lateral conveyer, and means for varying the speed of the said drive means of the lateral conveyer.
6. In a machine of the class described, a longitudinal main conveyer frame, a conveyer carried thereby and including a sprocket chain, a carriage longitudinally movable on the frame, a lateral conveyer carried by the carriage, means for driving the lateral conveyer operable from the sprocket chain, and means for moving the carriage operable from the sprocket chain.
7. In a machine of the class described, a longitudinal main conveyer frame, a conveyer carried thereby and including a sprocket chain, a carriage longitudinally movable on the frame, a lateral conveyer carried by the carriage, a shaft on the car-

riage, a sprocket wheel on the shaft meshing with the main conveyer sprocket chain, a drive connection between said shaft and the lateral conveyer, and means driven from said shaft for propelling the carriage.

45

8. In a machine of the class described, a longitudinal main conveyer frame, a conveyer carried thereby and including a sprocket chain, a carriage longitudinally movable on the frame, a lateral conveyer carried by the carriage, a shaft on the carriage, a sprocket wheel on the shaft meshing with the main conveyer sprocket chain, a drive connection between said shaft and the lateral conveyer, a second shaft, means cooperating with said second shaft for moving said conveyer along said main conveyer frame, and a reducing drive connection between the said shafts.

50

55

9. In a machine of the class described, a longitudinal main conveyer frame, a conveyer carried thereby and including a sprocket chain, a carriage longitudinally movable on the frame, a lateral conveyer carried by the carriage, a shaft on the carriage, a sprocket wheel on the shaft meshing with the main conveyer sprocket chain, a drive connection between said shaft and the lateral conveyer, a second shaft, means carried by said second shaft for moving said conveyer along said main conveyer frame, a reducing drive connection between the said shafts, and means for preventing rotation of the first named shaft.

65

70

In testimony that I claim the foregoing I have hereunto set my hand at Milwaukee, in the county of Milwaukee, and State of Wisconsin.
